UNITED STATES PATENT OFFICE.

JOHN E. LOGAN, OF KANSAS CITY, MISSOURI.

SHIPPING-CRATE.

1,231,178.

Specification of Letters Patent. Patented June 26, 1917.

Application filed February 16, 1914, Serial No. 819,084. Renewed March 2, 1917. Serial No. 152,150.

To all whom it may concern:

Be it known that I, JOHN E. LOGAN, a citizen of the United States, residing at Kansas City, in the county of Jackson and State of Missouri, have invented certain new and useful Improvements in Shipping-Crates, of which the following is a specification.

My invention relates to improvements in shipping-crates, and my object is to produce a light, substantial and inexpensive crate which is well adapted for shipping eggs, vegetables, fruit and other produce by parcel post, or express, without freezing or breaking.

In order that the invention may be fully understood, reference will now be made to the accompanying drawing, in which:

Figure 1 is a perspective view of the crate in open position.

Fig. 2 is a front elevation of the crate closed.

Fig. 3 is a detail perspective of a false-lid employed in carrying out the invention.

Fig. 4 is a detail side elevation of a spring fastener employed in carrying out the invention.

In carrying out the invention, I form the main body of the crate in two sections 1 and 2, connected by hinges 3, so that the crate may be closed or readily opened.

Sections 1 and 2 are provided with handles 4 and 4^a, whereby the crate can be readily carried when closed. The crate is reliably secured in closed position by hasps 5 secured to section 1, staples 6 secured to section 2, and spring fasteners 7 adapted to pass through the staples 6 and lock the hasps thereto, as shown on Fig. 2.

Each spring fastener comprises an intermediate coil 7^a, and two arms 7^b extending from said coil and curved at their outer terminals 7^c to reliably engage the opposite sides of its respective staple. With the spring fastener thus constructed, it is practically impossible for it to become accidentally removed from its staple 6, but when it is desired to open the crate the spring fastener can be quickly removed by pressing one arm 7^b against the companion arm 7^b and removing one of the terminals 7^c from the staple by rocking the fastener on the opposite terminal 7^c.

The upper surface of section 2 has a card holder 8 to hold a card which may contain

the address of the addressee on one side and the address of the addressor on the opposite side.

9 designates two pairs of hooks secured to opposite sides of sections 1 and 2 to overlap the ends of two pairs of bow-springs 10, secured by pivots 10^a to the intermediate portions of two false-lids 11 which are cut out at 12, so that they may pass downward over the hooks 9, and also to permit the fingers to be inserted beneath said false-lids when it is desired to remove the same from the crate.

13 designates a plurality of cells in sections 1 and 2, to receive eggs for shipment. Said cells are formed by strips of straw-board or other suitable material 14, intersecting each other at right angles, as shown. Strips 14 are detachably connected, so that they may be taken apart and placed in the bottom of either section 1 or 2, when it is desired to ship other produce than eggs. In order to prevent breaking or freezing of the eggs, the walls of each cell 13 are heavily padded with felt 15 and 16, and the undersides of the false-lids 11 are lined with felt 11^a to present a soft surface to the adjacent ends of the eggs. Space is left between the two false-lids 11 to give the false-lid which happens to be uppermost, room to spring downward and thus relieve the eggs of any crushing strain to which they might be subjected should a heavy weight be placed upon the crate and cause its upper side to spring downward.

The walls of the cells 13 are of such size as to relieve the eggs therein of all strain irrespective of the position the case is placed in, and any weight placed upon the crate when in closed position is carried by the walls of sections 1 and 2 and not by the strips 14 constituting the cells, hence there is no danger of the eggs becoming crushed.

From the foregoing description it is apparent that I have produced a shipping crate possessing the advantages above enumerated, and while I have shown and described the preferred form of my invention, I of course, reserve the right to make such changes in the construction, arrangement and proportion of parts as properly fall within the spirit and scope of the claim.

Having thus described my invention, what I claim and desire to secure by Letters Patent, is:

A shipping case comprising a pair of

hingedly connected sections, intersecting strips mounted in the sections and constituting cells, false lids for the sections having cut-outs formed in their side edges and 5 in registry with certain of the cells, hooks carried by the sections and overhanging the cells with which the cut-outs register, and bow springs pivotally connected to the lids, said springs serving to hold the lids in yielding engagement with the outer edges of the 10

strips forming the cells when the ends thereof are located in the cut-outs and engaged with said hooks.

In testimony whereof I affix my signature, in the presence of two witnesses.

JOHN E. LOGAN.
